DRESS OR LIKE GARMENT

Doris Brosk, 150 E. 16th St., New York, N.Y. 10021

Filed Apr. 13, 1970, Ser. No. 22,388

Term of patent 14 years

Int. Cl. D2—02

U.S. Cl. D2—81

The figure is a front elevational view of a dress showing my new design, the back being conventional, plain, and unornamented.

I claim:

The ornamental design for a dress or like garment, as shown and described.
